Primary Examiner — Lilyana Bekic(74) *Attorney, Agent, or Firm* — Themis Law(57) **CLAIM**

The ornamental design for a glass for snorkel mask, as shown and described.

DESCRIPTION

FIG. 1 is a perspective view of a glass for snorkel mask showing our new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken line showing of the snorkel mask depicts environmental structure and forms no part of the claimed design.
